US0D1072755S

(12) **United States Design Patent** (10) **Patent No.:** **US D1,072,755 S**
(45) **Date of Patent:** **** Apr. 29, 2025**

(54) **POWER SUPPLY**

(71) Applicant: **Ningbo JiuYuan Electronic Co., LTD.**,
Zhejiang (CN)

(72) Inventor: **Peng Zhou**, Ningbo (CN)

(73) Assignee: **Ningbo JiuYuan Electronic Co., LTD.**,
Zhejiang (CN)

(**) Term: **15 Years**

(21) Appl. No.: **29/916,299**

(22) Filed: **Nov. 9, 2023**

(30) **Foreign Application Priority Data**

Oct. 12, 2023 (CN) 202330660654.7

(51) **LOC (15) Cl.** **13-02**

(52) **U.S. Cl.**

USPC **D13/124**; D13/110

(58) **Field of Classification Search**

USPC D13/124, 104, 103, 107, 108, 110, 112,
D13/118, 119, 184, 199

CPC H02J 7/0042; H02J 7/0045; H02J 50/10;
H02J 7/0044; Y02T 90/14; Y02E 60/12;
H04M 1/04

(57) **CLAIM**

The ornamental design for a power supply, as shown and described.

DESCRIPTION

FIG. 1 is a top perspective view of a power supply showing my new design;

FIG. 2 is a bottom Perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings illustrate the portions of the power supply which form no part of the claimed design. The diagonal shaded lines indicate that the feature is transparent.

1 Claim, 8 Drawing Sheets
